UNITED STATES PATENT OFFICE

157,453

SCRAPER

Harold A. Wagner, Portland, Oreg.

Application July 14, 1948, Serial No. 147,569

Term of patent 14 years

(Cl. D14—3)

To all whom it may concern:

Be it known that I, Harold A. Wagner, a citizen of the United States, residing at Portland, in the county of Multnomah and State of Oregon, have invented a new, original, and ornamental Design for a Scraper, of which the following is a specification, reference being had to the accompanying drawings, forming a part thereof.

In the drawings:

Fig. 1 is a side view of the scraper;

Fig. 2 is a side view of the scraper illustrating the side opposite to that of Fig. 1;

Fig. 3 is a front view of the scraper;

Fig. 4 is a rear view of the scraper;

Fig. 5 is a plan view of the scraper.

I claim:

The ornamental design for a scraper, substantially as shown.

HAROLD A. WAGNER.
